UNITED STATES PATENT OFFICE.

PAUL M. BEARD, OF ST. LOUIS, MISSOURI, ASSIGNEE TO AMERICAN CAR AND FOUNDRY COMPANY, OF ST. LOUIS, MISSOURI, A CORPORATION OF NEW JERSEY.

DRAFT-GEAR.

1,123,069.

Specification of Letters Patent. Patented Dec. 26, 1913.

Application filed December 3, 1913. Serial No. 304,396.

To all whom it may concern:

Be it known that I, PAUL M. BEARD, residing at St. Louis, Missouri, and being a citizen of the United States, have invented a certain new and useful Improvement in Draft-Gear, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a plan view of the gear, half of which is shown in section on the horizontal center line D—D of Fig. 2. Fig. 2 is a vertical section on the center line E—E of Fig. 1. Fig. 3 is a section on line A—B of Fig. 1. Fig. 4 is an isometric view of the casing C which includes the frictional elements and receives their friction against its inner walls relieving the draft sills of spreading strains.

This gear is a modification of the ordinary tandem spring gear, designed so that under pulling strains there is no difference, but under buffing strains, which run greatly in excess of the pulling strains, there are added frictional elements introduced to help take care of these larger forces. This part of the force which the frictional elements absorb is taken up in such a manner that there is no spreading force exerted on the sills.

With my arrangement the danger of shearing the center tail strap rivets or buckling the tail strip is done away with as the pull or push is transmitted to the rear of the gear through a cast metal front tail strap portion so designed that no center tail strap rivets are required. My arrangement provides a stiff column for the transmission of strains and the danger of shearing the front tail strap rivets is obviated by the lugs K on the inner faces of the front tail strap receiving the thrust of the coupler.

While the central or frictional part of this gear is shown as taking up a little more room than the ordinary center thimble no

more space is required for the whole gear than in the ordinary construction on account of the rear rail strap being so arranged that it does not move back under buffing strains as the ordinary tail strap does.

By reference to Fig. 2 it will be seen that, in pulling, the front cast metal tail strap or yoke F through its lugs G acts as a unit with the rear tail strap H in compressing the springs in the usual manner, the friction elements simply riding free in the cast metal tail strap and performing no function. The only advantages of the gear under this movement being that the strain of compressing the front springs I is transmitted through the front cast metal tail strap itself instead of being transmitted from the tail strap through a center thimble which is secured to the tail strap with rivets in the ordinary construction and also that the use of two tail straps loosely engaging each other at the center of the gear will permit the front part of the gear to swivel at this central point in lining up with the coupler when the same is drawn to one side or the other while the car is passing around curves, which swiveling connection allows the rear part of the gear to remain on the center line of the car and exert a returning influence on the front of the gear and coupler.

By reference to Fig. 1 it will be seen that in buffing while the coupler, through the front follower 5, compresses the front spring I in the usual manner, instead of compressing the rear spring J through a thimble riveted between the tail strap as is the usual construction, in this improved form of gear this is done by the part L of the front tail strap pushing against the wedge shaped block M which, as it is moved rearwardly forces the wedge shaped friction blocks O rearwardly and these blocks force the wedge shaped block P against the spring J compressing this spring. Owing to the spreading action of the blocks M and P the blocks O frictionally engage the walls of the casing thereby adding frictional resistance to the resistance of the springs I and J. The casing C is held stationary by its lugs R which fit in recesses R' of the draft lug R'. In forward movement of the gear the pin S holds the friction elements in their pocket in the front cast metal tail strap. As the action of compression is taking place

the springs of course exert increasing resistance and as the resistance becomes greater so will the frictional resistance become greater, as these forces acting only through the blocks M and P will exert a corresponding increase of pressure of the friction blocks O against the walls of the casing C. When the gear has been compressed and the pressure ceases on the 10 coupler instead of having the quick recoil due to the expansion of the springs as in the ordinary spring gear, which recoil is an added strain on the equipment as well as causing jarring to the passengers, in this 15 gear the friction of the blocks O against the casing will retard the spring expansion until the springs have returned to their original position. This is a great advantage as overcoming the sudden rebound of 20 the ordinary spring gear.

The assembling of this gear is accomplished by first riveting the cast tail strap to the coupler and inserting the front spring I with its followers, then placing the frictional blocks in position between the top and bottom retaining walls I' which project from the body of the front tail strap, and dropping the retaining pin S in position, then sliding the rear tail strap over the 25 lugs G from the side and lastly sliding the inclosing casing C over the rear tail strap to its position and inserting the rear followers and spring. The whole is then lifted to place, the lugs R on the casing C sliding up in the receiving grooves of the draft lug, and supported in place by the usual follower slides T. It will be seen that the 30 top and bottom walls of casing C hold the rear tail strap from spreading. The front 35 tail strap rivets U having only the function of preventing the spreading of the tail strap can be very light, as the coupler impinging the lugs K of the forward tail strap 40

relieve the connecting rivets U of the stresses incident to buffing.

45

What I claim is:

1. In a tandem draft gear, a front tail strap having a rearward extension, a rear tail strap lapping said extension, a casing partly inclosing said extension and said rear tail strap, and friction producing means movable in said casing.

2. In a tandem draft gear, a box like casing and swiveling tail straps lapping with-in said casing.

3. In combination, draft lugs having mid portions adapted to serve as intermediate follower stops and having recesses therein, a casing anchored by said recesses, friction elements movable in said casing and a tandem draft gear comprising tail straps lapping within said casing.

4. In combination, lapping and swiveling tail straps, a casing inclosing the lapping ends of said tail straps, draft lugs co-operating with said casing to anchor it in position, friction producing means movable in said casing, and means for actuating said friction producing means.

5. In a draft gear, draft lugs, a casing anchored thereby, followers, tandem springs and tail straps, said tail straps lapping within said casing, and friction producing means in frictional engagement with said casing when movable in one direction.

75

6. In a tandem draft gear, in combination, alined springs and separable tail straps, a casing lapping said tail straps, and friction producing means co-operating with said casing.

80

In witness whereof I have hereunto set my hand in the presence of two witnesses.

PAUL M. BEARD.

Witnesses:

JAMES J. COOPER,

JOHN M. ROHEFING.
